UNITED STATES PATENT OFFICE

173,324

TEXTILE FABRIC

Henry A. Portong, Manhasset, N. Y., assignor to Everfast Fabrics, Inc., New York, N. Y.

Application March 8, 1954, Serial No. 29,412

Term of patent 3½ years

(Cl. D92—1)

To all whom it may concern:

Be it known that I, Henry A. Portong, a citizen of the United States of America, residing in Manhasset, county of Nassau, and State of New York, have invented a new, original, and ornamental Design for a Textile Fabric, of which the following is a specification, reference being had to the accompanying drawing, forming part thereof, wherein,

The figure on the drawing is a plan view of a textile fabric showing my new design.

I claim:

The ornamental design for a textile fabric, substantially as shown.
